TONE COMPENSATED VOLUME CONTROL

David E. Sunstein, Elkins Park, Pa., assignor to
 Philco Corporation, Philadelphia, Pa., a corpora-
 tion of Pennsylvania

Application April 29, 1944, Serial No. 533,367

4 Claims. (Cl. 179—1)

The present invention relates to volume control circuits, and more particularly to a circuit in which the volume may be lowered without disturbing the tonal balance.

In home radio receivers the reproduction of sound is ordinarily considerably lower in level than the level of the sound at the source. In order to reproduce sound at a lower level than the level at which the sound is generated, a tone compensation must be introduced in the reproducing system in order to maintain the same tonal balance existing in the original source of sound. Heretofore it has been shown by various authorities, including Fletcher, that the average human ear has a non-linear contour for a balanced relation of tones. This means that for the lower volume levels, the lower frequencies must be transmitted by a system having a rising characteristic below two thousand cycles.

Heretofore it has been recognized that in order to permit a reasonably balanced tonal reproduction of sound at lower volume levels, it is necessary to introduce some compensation in the sound reproducing system. Quite frequently this has been introduced by combining on a single control shaft two resistors, one connected in the volume control circuit, and another connected in a control circuit arranged to vary the response characteristic of the audio frequency transmission channel. In still other arrangements a multi-part circuit has been employed where the volume control is tapped at a certain point so as to be connected to a base compensation circuit. While such circuit arrangement provides some base compensation when the volume control arm is at or below the fixed tapped point on the resistor, this never has been regarded as entirely satisfactory. It, therefore, would be desirable to provide an improved circuit arrangement which permits the volume level to be reduced without disturbing the tonal balance in any appreciable amount. It furthermore is desirable to provide such circuit in a relatively simple form so as to be economical to manufacture and be available to the general public.

In accordance with the present invention these and other objectives are obtained by providing a circuit in which a variable resistor connected in series relation to an audio frequency transmission network serves to control the volume levels, and at the same time operates to produce tonal compensation so as to approximate the tonal balance required by the average human ear at lower volume levels.

It, therefore, is an object of the present in- 55

vention to provide an improved tone compensated volume control which is simple and reliable in operation.

It is a further object of the present invention to provide an improved tone compensated volume control which approximates at the various volume levels the tonal balance required by the average human ear.

Still another object of the present invention is to provide a tone compensated volume control circuit wherein a single variable resistor simultaneously functions to control volume and to effect tone compensation in a predetermined desired manner.

Other and further objects of the present invention subsequently will become apparent by reference to the following description taken in connection with the accompanying drawing, wherein

Figure 1 is a schematic representation of a tone compensated volume control circuit or network constructed in accordance with the present invention;

Figure 2 is a circuit diagram of the manner in which the basic circuit shown in Figure 1 may be incorporated in an audio frequency channel or amplifier;

Figure 3 is a graph in which the curves indicate the tonal balance required by the average human ear at different volume levels; and

Figure 4 is a graph showing various curves which illustrate the operation of the circuit shown in Figure 1.

The frequency response of the human ear varies with the sound intensity so that any artificial change in the volume of reproduced sound must be accompanied by a change in the frequency response of the sound reproducing system in order to maintain the same tonal balance existing in the original sound source. If it is assumed that the original sound intensity, as for example in a radio broadcasting studio, is at a level of fifty decibels any reproduction of such sound at a level below fifty decibels would have a different characteristic as is best illustrated by the curves shown in Figure 3. The curves shown in Figure 3 are response curves obtained by taking the difference between a contour at a level of fifty decibels and the contour obtained at lower volume levels based upon the response curves for the average human ear as given by Fletcher. Thus the curve A for reproduction at fifty decibels appears as a straight line where the abscissa are in frequencies covering a range from thirty to ten thousand cycles per second.

Curve B shows the curve obtained through the sound level of forty decibels. From the forty decibel volume level curve, it will be seen that the sound intensity required for a tonal balance comparable to the reproduction at fifty decibels requires a higher relative gain in the region below two thousand cycles. At lower volume levels, such as at thirty, twenty, ten or zero decibels as shown by curves C, D, E and F, there is still a greater difference required between the gain for the tones of frequencies below two thousand cycles and those above two thousand cycles. In order to provide a balanced reproduction at lower volume levels, it is necessary to provide an audio frequency current transmission network or channel which will introduce a compensation into the reproducing system so that the response curves obtain approach those shown in Figure 3.

A circuit which approaches the desired results indicated in the curves of Figure 3 is shown in Figure 1 wherein a symbol of the generator 11 represents a source of audio frequency currents which would produce in a loud speaker an intensity of fifty decibels. The source 11 is connected to a transmission network which includes a series connected adjustable resistor 12, and a shunt circuit comprising a fixed resistor 13 and a capacitor 14 arranged across the output terminals 15 and 16. It is assumed that the voltage appearing across the terminals 15 and 16 when the resistor 12 has been adjusted to zero value is sufficient to produce in a loud speaker energized from the output terminals 15 and 16 a volume having an intensity of fifty decibels. The ratio of the output voltage appearing across the terminals 15 and 16 to the input voltage supplied by the generator 11 is given by the following equation:

$$\left| \frac{e_0}{e_1} \right| = \left| \frac{R + \frac{1}{j\omega C}}{R + R_1 + \frac{1}{j\omega C}} \right| = \sqrt{\frac{1 + (wCR)^2}{1 + [w^2C^2(R + R_1)^2]}}$$

Therefore, the db attenuation is:

where R is resistor 13
R₁ is resistor 12
C is capacitor 14

$$db \text{ attenuation} = 10[\log(1 + (wCR)^2) - \log(1 + w^2C^2(R + R_1)^2)]$$

If the resistor 13 and the capacitor 14 are so chosen as to have a time constant of

$$\frac{10^{-3}}{2\pi}$$

the response produced by the reproducing device connected across the output terminals 15 and 16 corresponds to that shown in Figure 4. When the resistor 12 has been adjusted to zero value the reproduction is at a volume level of fifty decibels indicated by the straight line G. When the resistor 12 is adjusted so as to have a value equal to the resistor 13, the response follows the curve H and the curve I shows the response obtained when the resistor 12 has a value three times as great as the resistor 13. The curves J, L, M, N, O, and P show the response obtained when the resistor 12 is adjusted to values 7, 15, 31, 63, 127 and 255 times as great as the value of the resistor 13. From the graph shown in Figure 4, it becomes apparent that the circuit of Figure 1 is a close approximation to the ideal set forth as a requirement by the graph shown in Figure 3. At the lower volume levels it will be seen that the response curves at less than one thousand cycles

appear substantially parallel in Figure 4, whereas in Figure 3, the curves are not parallel. This difference between the lower intensity curves in Figure 4 produces an effect which gives an excessive amount of low frequency reproduction in the vicinity of one hundred cycles at about a thirty to forty decibels volume level.

In order to further compensate the reproduction of sound at the lower volume levels in the region of one hundred cycles a resistor approximately five times the value of the resistor 13 may be connected across the output terminals 15 and 16. Another manner of accomplishing a similar result or effect is to double the value of the capacitor 14 and to connect a capacitor having the same value in series with the resistor 12. This then produces a compensation which very closely approximates the various curves shown in the graph of Figure 3 at various volume levels with the exception of the very low levels in the vicinity of curves E and F where the reproduction will be slightly deficient in intensities of low frequencies.

For a practical application of the circuit of Figure 1 as further modified to produce the ultimate desired response characteristics, reference may be had to Figure 2 which shows audio frequency input terminals 17 and 18 which may be obtained from a detector or a phonograph pickup. The terminal 17 is capacitively coupled by a capacitor 19 to the control grid of a vacuum tube 21. The grid-to-cathode circuit of the vacuum tube 21 includes a resistor 22, and the cathode is connected to ground through a resistor 23.

The anode of the vacuum tube 21 is supplied by voltage from a suitable source and is by-passed to ground by a capacitor 24. The audio frequency component appearing across the cathode resistor 23 comprises a low impedance source of audio frequency currents which are to be supplied to the audio frequency transmission network embodying the present invention. This network includes a series capacitor 25 connected in series with an adjustable resistor 26 which is connected to the control grid of a succeeding audio frequency amplifier tube 27. A shunt circuit comprising a resistor 28 and a capacitor 29 is effectively connected across the output circuit of a network which is connected to the input circuit of the amplifier which includes the vacuum tube 27. The capacitors 25 and 29 may be of equal value each having a value two times as great as the capacitor 14 of Figure 1. The fixed resistor 28 corresponds to the resistor 13 of Figure 1, and the adjustable resistor 26 corresponds to the adjustable resistor 12 of Figure 1. A shunt resistor 31 is connected between the grounded conductor of the network, and the juncture between capacitor 25 and adjustable resistor 26.

The resistor 31 has relatively high resistance values compared to the resistor 13. Another resistor 32 is connected across the output of the network and this resistor has a value even greater than the resistor 31. The resistors 31 and 32 can thus be made to have a negligible effect on the frequency response produced by the transmission network and are included in the circuit to keep the maximum direct current resistance in the grid circuit of the first stage of the audio frequency amplifier, which may include the amplifier tube 27, to a value in the vicinity of one megohm.

Further application of the transmission network to a practical amplifier will be readily appreciated by an example of typical values of the

resistors and capacitors employed. It may be seen, for example, that the input resistor 23 which is a cathode load resistor for a vacuum tube has a value of about ten thousand ohms. The capacitors 25 and 29 each have a value of .32 microfarads which gives an effective series capacity of .16 microfarads, so that, together with the resistor 28 having a value of one thousand ohms, the time constant of the circuit is expressed by the equation

$$RC = \frac{1}{2000\pi}$$

seconds. The capacitor 25 also serves to keep the direct current in the cathode circuit of the vacuum tube 21 from appearing across the resistor 26. Preferably the resistor 31 has a value of at least 500,000 ohms and the resistor 32 has a value of 1.5 megohms. In order to attenuate the signal to the threshold of hearing level, and with the other values of the resistors as indicated, a zero to one megohm variable resistor 26 may be employed. The value of the resistor 28 preferably is kept at a relatively low value of the order of one thousand ohms so that the resistor 26 will be correspondingly small in resistance value so as to have a long life. For the practical application of the circuit as illustrated by the example given in connection with Figure 2, the over-all gain of the system should be such so that with the value of the resistor 26 adjusted to zero, the average loudness level of reproduced sound at the listener would be fifty decibels. In a radio receiver embodying such compensation circuit the automatic volume control or automatic gain control applied to the radio frequency stages of the receiver should be substantially flat so that no gain control adjustment need be made when tuning from one station to another.

Where the circuit is to be used in a manner as illustrated by Figure 2 in connection with a phonograph reproducing system, it may be desirable to produce a high frequency cutoff above five thousand cycles per second to reduce noise and high frequency distortion. Such cutoff may be embodied in the amplifier, which includes the vacuum tube 27. However, in such event this should have a rising characteristic from approximately fifteen hundred cycles to four or five thousand cycles in order to maintain approximate tonal balance.

From the above description it will be seen that there has been provided an audio frequency transmission circuit or network which is relatively simple, and in which a single variable resistor serves to control the volume level and simultaneously operates to introduce a compensat-

ing effect into the reproduced sound so as to maintain substantially the same tonal balance existing in the original sound source. Such circuit arrangement, therefore, eliminates the necessity of supplying a tone control device to compensate for changes in volume level in a phonograph or radio receiver. The base compensation is such that kettle drum, bass violins, and other orchestral instruments generating low frequency sounds will appear in the same general prominence regardless of the volume control setting.

While for the purpose of illustrating and describing the present invention, certain specific embodiments have been disclosed, it is to be understood that the invention is not to be limited thereby since obviously such variations in circuit arrangements and in the instrumentalities employed may be made as will be commensurate with the spirit and scope of the invention as defined in the appended claims.

The present invention is hereby claimed as follows:

1. In an audio frequency system, a source of audio frequency signals, a volume control circuit constructed and arranged to maintain an apparent tonal balance throughout the volume range, said volume control circuit having a pair of input terminals and a pair of output terminals, means for coupling said source to said input terminals, a variable resistor connected between one of said input terminals and one of said output terminals, and a fixed resistance and a fixed capacitance connected in series across said output terminals, the time constant of said series-connected elements being of the order of

$$\frac{10^{-3}}{2\pi}$$

second, said variable resistor being adjustable between a minimum value of approximately zero ohms and a maximum value of the order of hundreds of times the value of said fixed resistor, whereby variations in volume level may be effected without substantially disturbing the tonal balance.

2. An audio frequency system, as claimed in claim 1, characterized in that said fixed resistor has a value of the order of one thousand ohms.

3. An audio frequency system as claimed in claim 1, wherein said variable resistor is variable between the limits of approximately zero and one million ohms.

4. An audio frequency system as claimed in claim 1, characterized in that the said source comprises the load resistor of a cathode-loaded amplifier stage.

DAVID E. SUNSTEIN.
